UNITED STATES PATENT OFFICE.

CHARLES T. A. SIBBALD AND JOHN B. RANSOM, OF TROY, NEW YORK, ASSIGNEES, BY
MESNE ASSIGNMENTS, TO FREDERICK OSANN COMPANY, OF NEW YORK, N. Y., A
CORPORATION OF NEW YORK.

METHOD OF SEWING ON BUTTONS.

Original application filed April 27, 1922, Serial No. 557,011. Divided and this application filed June 23, 1924. Serial No. 721,650.

This invention relates to a method of sewing on buttons whereby the stitches are widely distributed in the material by more points of anchorage than there are holes in the button so that they can not be readily torn therefrom and to the attachment of buttons by this method, the subject matter of the present invention being divided out from our application for patent Serial No. 557,011, filed April 27, 1922, for button sewing machine, in which is disclosed a machine for sewing on buttons according to this method.

More particularly this invention relates to a method of so relatively manipulating a two hole button and the material that the attaching stitch loops pass through the two holes in the button and through four spaced portions of the material. This is done by moving the material relative to the button in a direction transverse to a line joining the holes of the button during the sewing operation so that stitches are passed through holes in the button and through the material in two relative positions of the button and material spaced apart in a direction transverse to a line joining the holes in the button.

For a more complete understanding of this invention reference may be had to the accompanying drawings in which—

Figures 1 to 10 are diagrammatic illustrations of the successive steps in attaching a two hole button according to the method of this invention.

Figure 11 is a diagrammatic view illustrating the engagement of the stitch loops as effected by a single thread machine on the back face of the material before the completion of the sewing operation.

Referring to Figures 1 to 10, 2 indicates a sewing machine needle, though it is evident that the type of needle is of no importance, 61 is a two hole button having holes 59 and 60 therein. 62 indicates the material to which the button is to be attached and 64 is a needle plate on which the material rests and which has a hole 63 through which the needle passes on its sewing or piercing and its oppositely directed retracting strokes.

In the initial stitch the needle 2 enters the hole 59 in the button, drawing the thread

therewith, and passes down through the material 62 and through the hole 63 in the needle plate 64 as shown in Figure 1. Following the usual looper movement the needle returns to above the plane of the button and immediately following this operation the material is moved relative to the button and sewing mechanism laterally to arrange the hole in the material through which the initial stitch passed out of alignment with the hole in the button as shown in Figures 2 and 4. The end of the thread is thus offset from the aligned holes 59 in the button and 63 in plate 64, causing the material to exert a binding action upon the thread which extends between it and the top of the needle plate 64, as shown in Figure 4, 70 this preventing the end of the thread from being drawn up through the hole in the button in a subsequent stitch. Both the button and the material are then moved relative to the needle and needle plate so that the needle successively stitches through the holes 60 and 59 alternately and through the material therebetween as shown in Figures 5, 6, and 7. The end of the thread is shown at *m* on Figure 11 and the succeeding 80 stitches are shown as chain loops at *n*, *p* and *q*.

Following a predetermined number of stitches through the holes in the button and the material, the material is again moved 85 relative to the button and stitching mechanism transversely of a line joining the holes in the button, as shown in Figures 8 and 11, thus bringing the initial stitch *a* again in alignment with the hole 59 of the button so that on subsequent stitching through the hole 59 of the button the stitches pass 90 through the material close to this initial stitch and lies on the back of the material as loops *r*, *s*, *t* (Figure 11). The large loop 95 *u* shown in Figure 11 is the loop last made, which, when the work is in the machine, would be engaged over the looper for the passage of the next loop therethrough on the next descent of the needle. The holes 100 in the material through which the previous series of stitches passed are then out of line with the holes in the button as shown in Figures 8, 10 and 11. The stitching is continued alternately through the two holes 105 of the button and through the material

until the required number of stitches have been made, this resulting in two groups of stitches extending over the button from one to another hole and having loops passed through each hole of the button and diverging to and from its lower end through spaced portions of the material as shown best in Figure 10, the diverging groups *a*, *a'* and *b* passing through the hole 59 of the button and the diverging groups *c* and *d* passing through the hole 60. It will thus be seen that the two hole button is secured to the material at four distinct spaced points of anchorage. It will be noted that the button and the material are maintained in substantially the same angular relation throughout the stitching operation, being substantially parallel to each other at all times.

Having thus described this invention it should be evident that various changes and modifications might be made therein without departing from its spirit or scope as defined by the appended claims.

We claim:—

1. A method of securing buttons having a plurality of holes to material which consists in stitching by alternate material piercing and oppositely directed retracting needle strokes through the holes in the button to the material, and then relatively moving the button and material so that the stitches through the holes will be anchored in the material out of line with the holes in the button through which they pass, then subsequently stitching by a continuation of such strokes through the same holes in the button in that part of the material then alined therewith.
2. The herein described method of securing a button having a plurality of holes to material which consists in stitching through the holes in succession by alternate material piercing and oppositely directed retracting needle strokes, and passing a portion of said stitches through the material at definite anchorage points and the remaining portion of said stitches through the same holes in the button and through the material at other definite anchorage points spaced from said first mentioned anchorage points.
3. The herein described method of securing a plural hole button to material which consists in passing stitch loops alternately through the holes in the button and anchoring said loops through the material at a number of points in excess of the number of holes in the button.
4. The herein described method of securing a two hole button to material which consists in placing a plurality of loop stitches through the holes in the button alternately, and moving the material relative to the button to another position following a predetermined number of such stitches less than the

whole, whereby to provide four anchorage points for the stitches in the material.

5. The method of securing a plural hole button to material which consists in passing stitching loops through the holes in succession and diverging the loops from each hole to and through spaced points in the material.

6. The method of securing a plural hole button to material which consists in passing stitches alternately through the holes in the button and anchoring said stitches through the material at a number of points different from the number of holes in the button while maintaining the angular relation between the button and the material substantially constant.

7. The method of securing a plural hole button to material, which consists in passing stitches alternately through the holes in the button, and while maintaining the button and material in substantially parallel planes, anchoring the stitches in the material at points in excess of the number of holes in the button.

8. The method of sewing a button to material which comprises stitching the button to the material by a plurality of stitches, then shifting the button relative to the material while maintaining their angular relation substantially constant, and then continuing the stitching in substantially the same relation to the button but engaging the material at points spaced from the first stitches.

9. Means for attaching a button to material, which comprise stitches passing over the button from one to another hole therethrough, and having loops passing through said holes and through a different number of holes in the material.

10. Means for attaching a button to material, which comprise stitches passing over the button from one to another hole therein, and having loops passed through said holes and extending from each of said holes to spaced points in the material.

11. Means for attaching a two hole button to material, which comprise stitches passing over the button from one to the other hole, and having loops extending through said two holes and engaging the material at four spaced points.

12. Means for attaching a button to material, which comprise stitches passing over said button from one to another hole in the button, and having loops extending through said holes and engaging each other in chain stitch formation on the back face of the material, the loops extending from one hole in the button to the material engaging the material at a plurality of spaced points.

13. Means for attaching a button to material which comprises two groups of loop stitches passing through each hole of the

button, the stitches of the respective groups diverging from the holes of the button and engaging the material at spaced points.

14. Means for attaching a button to material, which comprise loop stitches passing through a hole in said button, the stitches emerging from one end of said hole diverg-

ing and extending to and engaging the material at spaced points.

In testimony whereof we have affixed our 10 signatures.
